(57) **CLAIM**

The ornamental design for a tool box as shown and described.

DESCRIPTION

FIG. 1 is a left perspective view of a tool box showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a left perspective view thereof in an separated state; and,

FIG. 9 is a left perspective view of the lower part of the tool box in an open state.

The lower part of the tool box is shown separate in FIG. 9 for ease of illustration only. The broken lines illustrate portions of the tool box that form no part of the claimed design.
